UNITED STATES PATENT OFFICE.

JOHN U. JONES, OF DALLAS, TEXAS.

VALVE FOR ENGINES AND MOTORS.

Application filed June 24, 1925. Serial No. 39,395.

This invention relates to new and useful improvements in valves for engines and motors.

The object of the invention is to provide a valve which may be used for air, oil and steam in combination or separately in proper proportions and without the use of the other fluids and under high pressure and high temperatures, as the case may require.

10 A particular object is to provide a valve which will enable an engine or motor to be built with standard frame sizes, shafts etc., and by use of said valve converted from a combined steam, air and oil engine to a condensing or non-condensing steam engine, or to an oil engine under the two cycle principle, single or double acting and which may be built either horizontal or vertical.

20 An important object of the invention is to provide a common valve for performing the dual function for atomizing the fuel charge and also for supplying the necessary fluid under pressure for blowing out the scavenging gases or products of combustion through the exhaust opening.

30 A further object is to provide a valve whereby a better process of atomizing and scavenging can be obtained with a more simple and efficient means for performing these functions than has been heretofore evolved.

Another object is to provide a valve in the form of an attachment which may be connected in the head of an engine without material alteration of the latter.

35 A construction designed to carry out the invention will be hereinafter described together with other features of the invention.

The invention will be more readily understood from a reading of the following specification and by reference to the accompanying drawings, in which an example of the invention is shown, and wherein:

45 Fig. 1 is a fragmentary elevation of an engine cylinder equipped with a valve constructed in accordance with my invention, a portion being illustrated in section,

Fig. 2 is a vertical sectional view,

50 Fig. 3 is a cross-sectional view on the line 3—3 of Fig. 2,

Fig. 4 is a detail of the atomizing head and nozzle, and

Fig. 5 is an under side view of the same.

In the drawings the numeral 10 designates a cylinder of an engine having exhaust ports 11 of the cage type. A piston head 12 is slidable in the cylinder and has a sump 13

in its compression end. An annular head 14 is secured on the cylinder by means of bolts 15 and has a concentric water space 16. Such parts are found in many engines and are secondary to my invention.

The head has an inwardly tapered central bore 17 considerably less in diameter than the bore of the cylinder. A tapered valve case 18 is tightly fitted into the bore 17 and has an outwardly directed flange 19 overlapping the head 14 to which it is fastened by cap screws 20. The valve case has a central tube 21 extending therethrough and projecting outwardly a substantial distance.

At the inner end of the tube I provide a chamber 22 into which is screwed a disk head 23 having its under surface convex. A plurality of nozzles 24 are radially mounted in the convex surface of the head so as to spread the discharge radially of the cylinder. These nozzles may vary in construction and arrangement and are shown in detail in Fig. 4. At the top of the chamber 22 I provide a valve seat 25 adapted to receive an upwardly seating valve head 26 carried by a valve stem 27.

The valve stem extends through a stuffing box 28 at the upper end of the tube and receives a cap 29; between the cap and the upper end of the tube a coiled expansion spring 30 is confined about the stem. This spring normally holds the head 26 seated.

Just under the stuffing box a pipe 31 enters the tube from one side, while a second pipe 32 enters the tube from the opposite side. Air or steam or both may be supplied through the pipe 32. It is to be understood that the steam or air may be omitted and the fuel oil alone utilized. The valve stem within the tube has a special thread 27', which causes the fluids passing down the tube to take a spiral course and whereby the molecules are more thoroughly broken up and a more complete mixture of the constituent elements is obtained. The charge ejected through the nozzle 23 will be fully atomized and highly combustible.

The tube within the valve case is surrounded by a vertical annular chamber 33. In the lower end of the chamber 33, (Fig. 2) are annular valve seats 36 and valve heads 37 seating upwardly against said seats. From each head 37 a stem 38 extends through the chamber and a stuffing box 39 in the upper end of the case. On each stem a coiled spring 40 is confined under a yoke, 41.

In the lower portion of the cavity 33 (Fig. 1) are ball valves 43 which are supported on apertured lower seats 44. These ball valves may be omitted and the work done entirely by the valves 37, which latter is preferable. Fluid supply pipes 45 enter the top of the chamber 33. Suitable means are provided for operating the valve 26 and the yoke 41 which operates the valve 37.

- 10 In operation the full charge is supplied through pipe 32 and air or steam or both are supplied through the pipe 31. This mixed fuel fluid passes down the tube, being given a spiral or whirling motion by the thread 15 27', whereby the molecules are broken up and atomization is promoted. The valves 37 will open when the piston head 12 uncovers the exhaust ports 11 at the bottom of its stroke and the fluid which has been stored 20 in the chamber 33, under pressure, will pass into the cylinder and blow out the scavenging gases through said exhaust ports.

The pipes 45 are provided with pressure regulated valves 46 of a suitable type arranged to open under a predetermined pressure. The valves 37 remain open and permit the pipes 45 to supply fresh air at atmospheric pressure, or air from a storage tank to the cylinder 10, which is thus filled above 25 the piston. During the up-stroke of the piston the valves 37 remain open, whereby the chamber 33 is filled with compressed air for scavenging and compression is built up at the top of the cylinder. These valves are 30 timed to close just prior to the opening of the valve 26 which admits the fuel charge through the nozzles 24. This traps the compressed air in the chamber 33. If the valves 35 43 are used they will close against their seats 44 immediately following the ignition of the charge and reduction of the pressure of the air in the cylinder.

It is also the purpose of the valves 37 to function for starting the engine. Compressed air for this purpose is supplied 45 through the pipes 45. A reversing mechanism (not shown) for reversing the time of opening of said valves for scavenging, will be employed, and thus the valves 37 will 50 open at the upper end of the stroke of the piston for admitting the starting pressure.

Where the engine is to be operated entirely on steam the valve 26 may be fastened and steam admitted through the pipes 45 or 55 otherwise supplied to the chamber 33. The valves 37 will then be timed to open at the upper end of the stroke of the piston. Other fuel adjustments are easily possible. The valve case 18 being a self contained unit and 60 readily fitted with the head 14, could be altered if necessary without changing the cylinder, head or other part. But by manipulating the parts of the valve, as described, the engine may be converted from 65 oil to steam or air or any other combination

and offers an economical power plant adjustable to the conditions which might arise.

Various changes in the size and location of the various parts and modifications are contemplated within the scope of the appended claims.

What I claim, is:

1. In an engine valve mechanism, the combination with a cylinder having an exhaust port, and a piston working in said cylinder, of a valve device operative on the suction stroke of the piston for admitting a fuel charge to the cylinder, said valve device being provided with a fluid storage chamber and means governing the flow of fluid back and forth between said storage chamber and the cylinder, said means coacting with the piston, in the movements of the latter, for establishing communication between the storage chamber and cylinder and supplying fluid independent of the fuel charge to the cylinder on the suction stroke of the piston, for maintaining communication between the storage chamber and cylinder during a portion of the compression stroke of the piston for storing up such fluid under piston pressure in said chamber and then closing communication between the chamber and cylinder, and for releasing said pressure on the working stroke of the piston and when the exhaust port is open to blow out the gases remaining in the cylinder.

2. In a valve mechanism, the combination with a cylinder having an exhaust port, a piston working therein, of a valve case having a central tube, an atomizing head at the lower end of the tube, a valve seating in the tube above the head, and a pressure supply chamber in the case having an inwardly opening valve controlling communication with the cylinder.

3. In a device of the character described, a valve case having a fuel charge conducting tube and a fluid pressure chamber, a fuel valve controlling the passage through said tube, and a second valve for said chamber controlling the passage of fluid to and from an engine cylinder.

4. In a device of the character described, a valve case having a fuel charge conducting tube and a fluid pressure chamber, a fuel valve controlling the passage through said tube, and a second valve for said chamber controlling the passage of fluid to and from an engine cylinder, said chamber having a fluid pressure inlet for admitting a fluid thereto.

5. In a device of the character described, a combination valve mechanism including a fuel charge valve for introducing combustible fuel charge to a cylinder, and a second valve for introducing a fluid either in conjunction with the charge valve or independently thereof.

6. In a device of the character described,

- a valve case having a fuel charge passage and a chamber, an atomizing head connected with the passage, a fuel valve between the head and passage, means in the passage for causing the fuel charge to pursue a helical path, and a second valve controlling communication between the valve chamber and the cylinder of an engine.
7. In a valve mechanism, the combination with a cylinder having an exhaust port, and a piston working in the cylinder, of a valve device having a valve open upon the up-stroke of the piston to receive a self compressed charge of fluid, said valve being closed before the ignition of the fuel charge, and again opened to release the compressed fluid to scavenger the cylinder when the piston uncovers the exhaust port.
8. In a valve mechanism, the combination with a cylinder having an exhaust port, and a fluid storage chamber, and a piston working therein, of means independent of fuel supplying means and including a valve device, coacting with the piston, for storing up fluid pressure in said chamber, admitting passage of said pressure from said chamber to the cylinder when the exhaust port is open, and cutting off the flow of pressure to the cylinder when the exhaust is closed and the piston has moved to a predetermined degree on its compression stroke.
9. In a device of the character described, a cylinder, a piston working therein, a valve case having a fuel charge passage and a chamber, an atomizing head connected with the passage, a fuel valve between the head and passage, and a second valve controlling the flow of fluid pressure between the chamber and the cylinder, said valve being adapted to open on the down-stroke of the piston, remain open during a portion of the up-stroke of the piston, and then close to cut off communication between the chamber and cylinder.
10. In an engine, a cylinder having a fuel inlet and a central exhaust outlet, a fluid pressure chamber, a piston operating in the cylinder, and a valve mechanism for admitting fuel to the cylinder through said inlet during the final portion of the working stroke and preliminary portion of the compression stroke of the piston, said valve mechanism also operating to open communication between and admit fluid to the cylinder from the fluid pressure chamber during the final portion of the working stroke of the piston, to maintain communication between said cylinder and chamber during a portion of the compression stroke of the piston, whereby a portion of the compressed fluids in the cylinder will be forced back into the chamber for storage therein, and to cut off communication between the cylinder and chamber before the completion of the compression stroke of the piston.
11. In an engine, a cylinder having a fuel inlet and a central exhaust outlet, a fluid pressure chamber, having a check-valved inlet, a piston operating in the cylinder, said piston adapted on its working stroke and when the chamber is in communication with the cylinder to form a partial vacuum in said cylinder, whereby fluid is drawn thereto through said check-valved inlet, and a valve mechanism for admitting fuel to the cylinder through said inlet during the final portion of the working stroke and preliminary portion of the compression stroke of the piston, said valve mechanism also operating to open communication between and admit fluid to the cylinder from the fluid pressure chamber during the final portion of the working stroke of the piston, to maintain communication between said cylinder and chamber during a portion of the compression stroke of the piston, whereby a portion of the compressed fluids in the cylinder will be forced back into the chamber for storage therein, and to cut off communication between the cylinder and chamber before the completion of the compression stroke of the piston.
12. In a device of the character described a cylinder, a piston working therein, a valve case having a fuel charge passage and a chamber, a fuel valve controlling said passage, and a second valve controlling the flow of fluid pressure between the chamber and the cylinder, said valve being adapted to open on the working stroke of the piston, remain open during a portion of the compression stroke of the piston, and then close to cut off communication between the chamber and cylinder.

In testimony whereof I affix my signature.
JOHN U. JONES.
